UNITED STATES PATENT OFFICE.

JOHN J. MAHLER, OF NEW YORK, N. Y., ASSIGNOR TO UNITED SHOE MACHINERY CORPORATION, OF PATERSON, NEW JERSEY, A CORPORATION OF NEW JERSEY.

LAST.

Application filed September 18, 1924. Serial No. 738,426.

This invention relates to lasts for use in the manufacture of stitchdown shoes. In my prior application Serial No. 717,017, filed May 31, 1924, I have disclosed a last 5 by the use of which stitchdown shoes of a superior quality have been produced and it is an object of this invention to provide an improved last which, without sacrificing any of the advantages of my prior invention, will 10 still further facilitate the manufacture of stitchdown shoes.

As has been fully set forth in my prior application above referred to, one of the conditions which has prevented more extended 15 commercial success of the stitchdown type of shoe has been the difficulty of making shoes of this type in which the upper and welt were secured sufficiently over the last bottom to provide a well defined welt crease such as 20 is characteristic of well made shoes of other kinds. Accordingly, another object of this invention is to provide an improved last by the use of which a well defined welt crease may be produced.

25 Further objects of the invention are to provide a last having a well defined corner adjacent to its bottom over which the upper is lasted and shaped so that the upper of a shoe made thereon will have a well defined 30 line about its greatest periphery and the appearance of the shoe will be thereby improved; to provide a last so constructed as to afford more room for the nozzle of a staple lasting machine to enable it to work the upper 35 farther over the last bottom and to avoid objectionable bending of the margin of the sole to which the upper is stapled out of the plane 40 of its central portion; and to provide a last by the use of which the table of the outsole of a stitching machine can force the upper and welt inwardly beyond the line of greatest periphery of the last and closely against the edge face of the innersole.

With these objects in view, features of the 45 invention consist in a last having a reentrant angular space about the forepart between the side of the last and the bottom of the last and outside of the area covered by the innersole. This space may, as shown herein, be 50 provided by forming a rabbet in the last at the edge of the last bottom, the sides of the rabbet being preferably the one parallel to and the other perpendicular to the last bottom. The side of the rabbet may be substantially 55 equal to each other in width or, as

shown, the side of the rabbet which is parallel to the last bottom may be slightly wider than the side which is perpendicular to the last bottom. The width of these sides may vary with respect to each other and either or both may be wider or narrower, according to the kind of shoe being made or other working conditions.

In the drawings,

Fig. 1 is a bottom view of a last embodying 65 the present invention;

Fig. 2 is a transverse section of the last on the line 2—2 of Fig. 1;

Fig. 3 is a transverse section, on an enlarged scale, of the last and a partly completed shoe showing the operation of stapling 70 the upper to a middle sole;

Fig. 4 is a transverse section, on an enlarged scale, of the last and a shoe during the 75 attachment of the welt and outsole;

Fig. 5 is a transverse section, on an enlarged scale, of the last and a completed shoe; and

Fig. 6 is a perspective view of the forepart 80 of a shoe partly broken away to expose the last and show the shoe structure.

A last 2 embodying the present invention, as shown in Fig. 1, is, in general, of the usual type used in the manufacture of welt shoes, the bottom being of wood except at the heel-seat where the usual metal plate 4 is provided. About the forepart 6 of the last from one end of the ball line to the other end of the ball line a rabbet 8 is formed which has nearly equal sides, one side 10 being, as shown, substantially perpendicular to the last bottom and the other side 12 being substantially parallel to the last bottom, the sides meeting at substantially a right angle 14. The rabbet therefore forms a reentrant angle between the side of the last and the bottom of the last.

The dimensions of the rabbet may, of course, be varied without departing from the invention. It has been found in practice that good results are obtained when the side 10 of the rabbet is 5/64 and the side 12 is 7/64 of an inch in width. The dimensions of the rabbet are preferably the same in all sizes of lasts of a given style. As shown, the dimensions of the rabbet are uniform throughout its extent.

It is to be understood that although the last is well adapted for use in the manufacture of single-sole or two-sole stitchdown shoes, it is of special utility when employed 110

in the manufacture of three-sole stitchdown shoes, as herein shown. An innersole *a* is provided which will cover the bottom of the last and lie with its edge face substantially flush with the side 10 of the rabbet. This innersole is temporarily secured to the last and an upper assembled thereon and preferably pulled over. The lining *b* is then lasted in and secured to the bottom of the sole *a*, preferably by cement. After removing the fastenings which hold the innersole to the last, a middle sole *c*, larger than the innersole, is applied to the innersole and temporarily secured. The upper *d* is then lasted to the middle sole, for example, as shown in Fig. 3, by the use of a stitchdown staple lasting machine. In this operation the upper is drawn down the side of the last and against the sharp angle 16 formed by the side of the last and the side 12 of the rabbet, so that a well defined line is produced about the shoe at its greatest periphery similar to that produced in a welt shoe in lasting the upper over the feather of the innersole. The upper is forced firmly against the middle sole *c* at a point inwardly of the said angle 16 and stapled to the middle sole by a clinched staple *e*, this operation being repeated, of course, a sufficient number of times to cause the upper to be held in lasted position about the periphery of the last. In this operation the upper and lining are more or less bridged across the angle formed by the side 12 of the rabbet and the side 10 of the rabbet plus the thickness of the innersole *a*, this angle affording ample space for the operation of the staple nozzle in crowding the upper into the angle between the edge face of the innersole and the projection of the middle sole *c*. The driver of the stapling machine projects slightly beyond the end of the nozzle at the completion of its driving movement and hence causes the staple to draw the upper more sharply into the angle between the edge face of the innersole and the projection of the middle sole than is accomplished by the action of the nozzle alone.

The shoe is now ready for the attachment of an outsole *f* which is of the same size as the middle sole *c*. The fastenings holding the middle sole *c* to the last are removed, the outsole laid and the shoe presented to the outsole sewing machine. In this operation, as indicated in Fig. 4, a stitchdown welt *g* is guided by the work table 10 of the machine

into position on the flange of the outturned upper and is forced, with the upper, well into the reentrant angle between the side of the last and the bottom of the last. The pressure of the inner edge face of the welt against the upper forces it against the edge face of the innersole *a* and reduces the length of the bridged portion of the upper. A short portion, however, will still be bridged across the angle of the rabbet and will enable the welt, under varying conditions of the shoe materials, to press the upper against the edge face of the innersole at all points about the periphery of the shoe. The outsole stitches are indicated at *h*.

The provision of a rabbet at the edge of the last bottom enables the inner edge of the welt to be carried well under the overhang of the last and effectively concealed; it provides a sharp angle between the side of the last and the side 12 of the rabbet which gives a definite line to the shoe upper about the periphery of the shoe and improves its appearance; it, together with the thickness of the innersole, provides space for the operation of the staple nozzle so that the usual tendency for the margin of the middle sole to be bent out of the plane of the last bottom during the stapling operation is minimized; and it enables the shoe to be given a well defined welt crease which enhances the appearance of the shoe and increases its market value.

Having thus described my invention, what I claim as new and desire to secure by Letters Patent of the United States is:

1. A last for use in the manufacture of stitchdown shoes having about its forepart a reentrant angle formed by plane surfaces between the side of the last and the bottom of the last.

2. A last for use in the manufacture of stitchdown shoes having between the side of the last and the last bottom a reentrant angle one side of which is perpendicular to the last bottom and the other side of which is parallel to the last bottom.

3. A last for use in the manufacture of stitchdown shoes having a right angled rabbet between the side face of the last and the last bottom, said rabbet extending about the forepart only of the last.

In testimony whereof I have signed my name to this specification.

JOHN J. MAHLER.
